UNITED STATES PATENT OFFICE.

CHARLES H. CLARK, OF NEW YORK, N. Y.

REDUCTION-GEARING.

1,142,401.

Specification of Letters Patent. Patented June 8, 1915.

Application filed March 5, 1912. Serial No. 681,792.

To all whom it may concern:

Be it known that I, CHARLES H. CLARK, a citizen of the United States, residing at New York, in the county and State of New York, 5 have invented certain new and useful Improvements in Reduction-Gearing, of which the following is a full, clear, and exact description.

In the use of prime movers in which the power shaft rotates at a high rate of speed it is in many cases necessary to reduce the speed by means of reducing gears or other mechanical devices for the purpose, in order to employ such prime movers efficiently for driving purposes where a relatively low speed is demanded. This is particularly true in the case of prime movers of the so-called turbine type, in which, as is well known, the rotor revolves at a very high speed; whereas the apparatus to be driven, as for example the propeller or side-wheels of a ship, frequently requires a speed far below the minimum speed of the turbine. Such requirements have led to the development of various "reducing" devices. Some of these devices are notoriously impracticable, while others which promised well have not accomplished the results anticipated for them. Even the best have, as is well known, been found to possess drawbacks which militate seriously against their extensive use and confine their employment to special conditions. One of the chief of the drawbacks referred to is size or bulk, and weight, the reducing mechanism often being in size and mass far in excess of that permitted by the surrounding conditions. This excessive bulk and weight is necessary, in the prior devices, to give the necessary strength and durability. This and other disadvantages found in various types of reducing mechanisms heretofore proposed have led me to devise my present invention, which has for its chief object to provide a speed-reducing system of high efficiency but of small size and cost.

To this and other ends the invention consists in the novel features of construction and combinations of elements hereinafter

described, and more particularly set forth in 50 the appended claims.

A convenient and effective embodiment of the invention is illustrated in the accompanying drawings, in which—

Figure 1 shows the apparatus in longitudinal section, Figs. 2, 3 and 4 are cross sections on lines 2—2, 3—3, and 4—4 respectively.

In the drawings, the part 10 represents the shaft of the turbine or other device, connected in any suitable manner to the power-receiving shaft 11 of the reducing gearing. In the present form of the invention the connection between the parts named consists of a series of spring-steel pins 12, between the alined shaft, the pins fitting tightly in apertures in the end of shaft 11 and in a collar 10^a having a square hole fitting the corresponding squared end of shaft 10, as shown, the object of such construction 60 being to provide a slight yield or give and so prevent sudden transmission of severe stresses from the power-driven shaft 10 to the reducing mechanism. The collar 10^a fits its shaft loosely enough to permit ready detachment therefrom and to permit the slight axial movement of the collar resulting from flexure of the spring-steel pins. The shaft 11 is journaled at one end in the end wall 13 65 of the casing 14 which incloses the mechanism. Bearing for the other end of the shaft is provided in the manner hereinafter described.

The shaft 11 is provided with wide teeth 15, and constitutes in effect an elongated 85 pinion. While for the best results the teeth on said shaft should be carefully formed, it is one of the advantages of my invention that the teeth 15, and others hereinafter mentioned, need not be of any special form, 90 but may be ordinary "gear teeth" without undue, if any, sacrifice of efficiency. It will be observed that the plain portion 16 of the shaft between the toothed portion and the bearing 13 is of the same diameter as the 95 said toothed or pinion portion.

Meshing with the pinion 15 at the end thereof next to the plain portion 16 of the

shaft 11 are three transmission gears 17, 18, 19, whose shafts, journaled in the opposite end walls of the casing 14, are spaced equi-
 5 angularly around the shaft 11, that is, 120° apart; said gears being in the same plane and being fixed on their respective transmission shafts 17^a, 18^a, 19^a, in any convenient manner. As will be seen, the teeth on these gears do not extend clear across the periph-
 10 eries thereof but leave the outer or right-hand portions (as viewed in Fig. 1) plain so as to make rolling contact with the plain portion 16 of shaft 11. Such plain or untoothed portions of the gears therefore con-
 15 stitute a roller bearing for the shaft mentioned.

In a plane at the left of that occupied by transmission gears 17, 18, 19 is a similar set of gears 20, 21, 22, arranged like the trans-
 20 mission gears first named but staggered with respect thereto, as clearly shown in Fig. 2. These gears are fixed on transmission shafts 20^a, 21^a and 22^a, respectively, journaled in the opposite end walls of the casing 14. As
 25 will be seen, the left-hand portions of the peripheries of gears 20, 21, 22 are plain, so as to make rolling contact with the left-hand plain or untoothed portion 23 of the shaft 11, thereby providing an additional roller
 30 bearing for the shaft, as will be readily understood.

The gears being alike in size and number of teeth it will be evident that they revolve at the same speed, lower than that of the
 35 shaft 11, but that each carries only one-sixth of the power delivered by said shaft.

The shafts 17^a, 18^a, 19^a, 20^a, 21^a, 22^a, are provided with pinions 24, 25, 26, 27, 28, 29 meshing with a gear 30 on a power-receiving
 40 shaft 31 arranged in axial alinement with the shafts 10 and 11 and mounted in the adjacent end-wall of the casing 14.

It will now be seen that the speed of the shaft 31 depends upon the ratio of the
 45 pinions 24, 25, 26, 27, 28, 29 to the gear 30, and that the speed of the pinions just named depends upon the ratio of the pinion 15 to the gears 17, 18, 19, 20, 21, 22, thus securing a very large reduction between the
 50 shafts 11 and 31. With an apparatus constructed as herein illustrated and described, designed to transmit 40 H. P. or more with the shaft 11 revolving at the rate of 3662 R. P. M., the gear ratios are such as to give
 55 shaft 31 a speed of only 183 R. P. M. At the same time, the gears and other metal parts of the mechanism are large and strong enough to transmit the whole of the power without liability of breakage or strain. The
 60 entire mechanism referred to is inclosed in a casing approximately ten inches in diameter and twelve inches long.

The shaft 31 may be connected in any
 65 convenient manner to the apparatus which is to be driven, as for example by means of

a spring coupling similar to that employed to connect shaft 10 and 11. For this purpose the shafts 31 and 32 (the latter being the shafts to which power is to be transmitted) are provided with flanged collars 70 33, 34, connected by a series of spring-steel pins 35. The collar 33 is keyed to its shaft, but collar 34 slips over the square end of shaft 32. The pins in both couplings make a driving fit with their sockets. 75

To prevent axial movement of shaft 11 toward the left it is arranged to abut against the recessed inner end of shaft 31, and to prevent rightward movement the shaft is provided with an axially movable collar 36 80 between the shaft 31 and the faces of gears 20, 21, 22, with a pin 37 extending through the shaft 11 with its ends projecting into slots 36^a in said collar, as shown in Fig. 1. It will therefore be seen that pressure tending to urge the shaft 11 toward the right will be resisted by the pin 37 pressing the collar against gears 20, 21, 22. The latter are held by the gears 17, 18, 19, against which they bear, while the last-named gears bear against the stationary end-wall of the casing. 85

It is desirable, in order to minimize liability of breakage or strain by unequal division of the load among the gears, that the shafts 17^a, 18^a, 19^a, 20^a, 21^a, 22^a, be accurately positioned, the gears themselves being made with sufficient care to insure proper working. To diminish the amount of care required to locate the bearings for the shafts the bearings in the end-wall of the casing through which the shaft 31 extends are first made and the parts assembled, but leaving the bearings in the other end-wall, for the shafts 17^a, 18^a, 19^a, 20^a, 21^a, 22^a, unbabbitted. The shaft 31 being then locked or held from rotation, in any convenient manner, a twisting stress is applied to shaft 11. This will cause all the gears and pinions to engage and assume their respective shares of the stress. The bearings in the end-wall through which the shaft 11 extends are now babbitted in any convenient manner, after which the stress applied to said shaft may be relieved, leaving the shafts and gears in the exact positions resulting from such stress. These positions may involve a slight twist, or bend, or both, of one or another of the shafts, but no more than such shafts, if made of suitable material, can well withstand. 90

In assembling the apparatus the shafts 17^a, 18^a, 19^a, with their gears, are first inserted in their bearings around the shaft 11, 110 after which the shaft 20^a, 21^a, 22^a, with their gears, are similarly positioned; the shaft 11 is next passed through its bearing 13; the collar 36 is now placed on shaft 11 115 and slipped back to the right far enough to expose the hole for the pin 37, after which 120

the pin is dropped into place and the shaft 11 retracted, thereby drawing the pin into the slots 36^a in the collar. The opposite end-wall, with the shaft 31 and gear 30 in place, is now brought into position on the casing, the shafts 17^a, 18^a, 19^a, 20^a, 21^a, 22^a, extending through their bearings and the pinions 24, 25, 26, 27, 28, 29, sliding into mesh with the gear 30. The last mentioned 10 end-wall is now secured in place.

To remove the driving pinion (the shaft 11) without removing the gears meshing with it, the driven shaft 31 is first drawn out, leaving the gear 30 supported by the 15 pinions 24, 25, 29, after which the shaft 11 is pushed in. This permits the collar 36 to be slipped back on the shaft, which allows the pin 37 to be removed. The shaft or pinion 11 can then be drawn out, leaving 20 the gears 17, 18, 22 in place.

From the foregoing description it will be seen that my invention provides an apparatus by which a large reduction of speed may be obtained, and that the apparatus 25 itself is compact in arrangement and also small in size. It will also be apparent that the apparatus can be used to increase instead of reduce speed, by applying the power to the shaft 31 and taking the power 30 from the shaft 11.

While the mechanism herein specifically illustrated and described is the preferred form of the invention, being highly efficient for the purpose intended, it is to be understood that the invention is not limited to 35 said mechanism but is capable of embodiment in other forms without departure from its proper spirit and scope as defined by the following claims.

40 I claim:

1. In a reduction gearing, in combination, a driving pinion; a plurality of shafts spaced around the driving pinion; gears on said shafts, meshing with the driving pinion 45 and driven thereby; a driven shaft in axial alinement with the driving pinion; a gear on the driven shaft; and pinions on said plurality of shafts, meshing with the last-named gear to drive the same and the driven 50 shaft, the driving pinion being removable axially without displacement of the gears meshing therewith.

2. In a reduction gearing, in combination, a driving pinion; a plurality of gears meshing with the pinion and rotatable on axes spaced around the pinion; a plurality of gears meshing with said pinion, arranged alongside the first-named gears and rotatable on axes arranged between the first-named 55 axes; pinions driven by said gears; and a gear meshing with said driven pinions and arranged in axial alinement with the driving pinion.

3. In a reduction gearing, in combination,

a driving shaft a pinion thereon; a plurality 65 of gears spaced around the driving shaft, having a portion of their peripheries in mesh with the pinion and a portion in rolling contact with the shaft on one side of the pinion; similar gears similarly arranged 70 having a portion of their peripheries in mesh with the pinion and in rolling contact with the driving shaft on the other side of the pinion; a driven shaft; and mechanism connecting the driven shaft with said gears 75 to drive the former.

4. In a reduction gearing, in combination, a driving shaft a pinion thereon; a driven shaft in axial alinement with the driving shaft; a plurality of gears arranged around 80 the driving shaft and meshing with the pinion; gearing connecting the said gears with the driven shaft to drive the latter; and means between the driven shaft and the gears to prevent axial movement of the 85 driving shaft away from the driven shaft.

5. In a reduction gearing, in combination, a driving shaft a pinion thereon; a driven shaft alined with and contiguous to the driving shaft; a plurality of gears arranged 90 around the driving shaft and meshing with the pinion thereon; a collar loosely encircling the driving shaft between said gears and the driven shaft, and removable means carried by the driving shaft and engaging 95 the collar to prevent axial movement of the driving shaft away from the driven shaft.

6. In a reduction gearing, in combination, a driving shaft and a pinion thereon; a plurality of gears meshing with the pinion and spaced around the driving shaft; a plurality of gears alongside the first named, meshing with the said pinion and having their axes between the axes of the first named gears; said gears serving as a supporting bearing 105 for the pinion and driving shaft; a driven shaft; and mechanism connecting the said gears with the driven shaft to drive the latter.

7. In a reduction gearing, in combination, 110 a driving pinion; three transmission gears meshing with the pinion in the same plane and having their axes spaced 120° apart; three transmission gears meshing with the same driving pinion in a plane alongside the 115 first gears and having their axes midway between the axes of the first gears; a driven shaft; a gear thereon; and six pinions connected coaxially with the driving gears and meshing with the driven gear to drive the 120 same.

8. In a reduction gearing, in combination, a casing having side walls and an end wall intergral therewith, and a removable end wall opposite the first, said end walls being 125 provided with alined bearings for a driving shaft and a driven shaft and having alined bearings for six shafts spaced equidistantly

around and from the first-named bearings; driving and driven shafts mounted in the first-named bearings; six transmission shafts mounted in the other bearings; six transmission gears mounted on the transmission gears in sets of three each, alongside each other; a driving pinion on the driving shaft, meshing with all the transmission gears; a gear on the driven shaft; and pinions on the

transmission shafts all meshing with the 10 gear on the driven shaft.

In testimony whereof I affix my signature in the presence of two subscribing witnesses.

CHARLES H. CLARK.
